UNITED STATES PATENT OFFICE.

KARL FRIEDRICH VOSS, OF COPENHAGEN, DENMARK.

RESTAURANT SIGNALING DEVICE.

Application filed June 26, 1926, Serial No. 118,786, and in Denmark June 9, 1926.

This invention is an improved restaurant signaling device especially adapted for use in signaling for a waiter or other attendant in a restaurant or other similar place, the object of the invention being to provide an improved device of this character which is simple in construction, which may be readily operated, is efficient in operation and which may be made in the form of a lamp and hence adapted for use not only as a signaling device but also as a lamp.

With the above and other objects in view, the invention consists in the construction, combination and arrangement of devices hereinafter described and claimed.

In the accompanying drawings

Figure 1 is an elevation of a restaurant signaling device in the form of a lamp and constructed and arranged in accordance with this invention.

Figure 2 is a detail vertical sectional view showing the upper portion of the standard and a portion of the signal carrying rod and its connections.

Figure 3 is a horizontal sectional view of the same on the plane indicated by the line A—B of Figure 2.

In the form of the invention here shown a tubular standard 2 rises from the center of a base 1, has a closed upper end and is provided in opposite sides with vertical slots 3. A lamp shade 15 is mounted at the upper end of the standard.

A vertically movable signal carrying rod 9 operates in a central opening in the closure of the upper end of the standard and is provided at its lower end with a cylindrical base 6 which is vertically movable in the standard and is provided with handles 5 which operate in the slots 3 and are provided at their outer ends with knobs 4 which may be readily grasped. At the upper end of the base 6 is a frusto-conical reduced portion 7 which has a circumferential groove 8. A split spring ring 13 is arranged in said groove and has a projection 14 directed inwardly.

A stop shoulder is arranged in the bore of the standard near the upper end thereof and is here shown as a bushing 11 which is fastened to the standard as by means of solder or the like and is provided with an annular groove 12 on its inner side. A source of light

such as an electric light bulb 10 which is preferably colored, mounted at the upper end of the rod 9 for vertical movement therewith and which, when the device is in normal arrangement, is used as a lamp, is in a lowered position and arranged within the shade 15.

For use for signaling a waiter or other attendant, the standard 6 is raised manually by means of the handles 5 or knobs 4 until said base 6 reaches the stop shoulder 11 and thus causes the light bulb to rise above the shade 15 and be prominently displayed, to catch the attention of an attendant, the split spring ring 13 which is carried by the base 6 snapping into the groove 12 and hence holding the light bulb in such elevated position. When the signal has been answered by a waiter, the standard 6 is pressed downwardly, the downward movement thereof causing the split spring ring 13 to disengage itself from the groove 12 as will be readily understood. To cushion the base 6 when it reaches the lower end of the standard and prevent noise, a cushion 18 which may be of rubber or other suitable material is provided in the lower end of the standard as indicated in dotted lines in Figure 1.

The base 1 is here shown as provided on one side with an ash receiver 17 and on the opposite side with a match case 16.

While I have herein shown and described a preferred form of the invention, it will be understood that modifications may be made in the form, construction and proportion of the several parts without departing from the spirit of the invention as defined in the appended claims.

Having now described my invention, what I claim is:

1. A signaling device comprising a tubular standard having a slot and provided with an internally arranged stop shoulder, a signal carrying rod having a cylindrical base vertically movable in said standard and provided with a handle which extends through said slot for manual operation of said signal bar and a spring carried by said stop shoulder and active to secure said signal rod.

2. A signaling device of the class described comprising a tubular standard having a vertical slot in one side and provided in its bore with a sleeve having an internal annular

groove forming a stop shoulder, a signaling element, a rod to which said element is attached, said rod having a cylindrical base vertically movable in the bore of the standard and provided with a reduced portion having an annular flange, a split ring spring mounted in the groove of said sleeve and

active to engage in said groove of the rod base to releasably secure the signal in raised position, said base having a handle extending through and movable vertically in said slot of the standard. 10

In witness whereof I affix my signature.
KARL FRIEDRICH VOSS.
